CLAIM

The ornamental design for a packing machine, as shown and described.

DESCRIPTION

FIG. 1 is a perspective view of a packaging machine;

FIG. 2 is a front view thereof;

FIG. 3 is a side view thereof, the right-side view being a mirror image thereof, except for some broken line subject matter on the opposite side of the large round roll.

FIG. 4 is a rear view thereof;

FIG. 5 is a top view thereof; and,

FIG. 6 is a bottom view thereof.
